ANTENNA

Albrecht Gothe, Berlin, Germany, assignor to
Telefunken Gesellschaft für Drahtlose Tele-
graphie m. b. H., Berlin, Germany, a corporation
of Germany

Application November 17, 1931, Serial No. 575,526
In Germany November 18, 1930

6 Claims. (Cl. 250--33)

This invention relates to an antenna arrangement adapted to different working waves.

It has been found in cases where the working wave is short that it is frequently necessary to feed the energy from the transmitter equipment to the aerial by way of what is known as an energy-feed line or up-lead. When working with only one fixed wave, adaptation between aerial and energy-feed line can be insured by the aid 10 of a tuned transformer. In special instances it is also feasible to insure such adaptation without a transformer. However, whenever the necessity arises to alter the wave-length, the condition of 15 adaptation is lost because this means a change of characteristic impedance and a consequent alteration in coupling or repeating resistance.

According to this invention, a change in the wave-length is accompanied by a change in the constants of the aerial, such change being insured by the alteration of the length of the antenna, so that for all waves the relationship between antenna length and wave-length and thus also the characteristic impedance remain unvaried. Hence, it is feasible in this manner to 20 secure adaptation between antenna and energy- 25 feed line (up-lead) throughout the entire working wave range, it being, by the way, immaterial whether the scheme is utilized for sending or for receiving. The particular method of varying the length of the antenna forms no part, per se, 30 of the present invention, but reference, however, is made to an arrangement suitable for adjusting the antenna length which is disclosed in an application Serial No. 674,024 filed by Werner 35 Buschbeck June 2, 1933, by way of example only.

The present invention shall be explained in more detail by the aid of three practical embodiments illustrated in Figures 1, 2 and 3 which represent antenna arrangements given by way 40 of illustration.

Referring to Figure 1, suppose the length of the aerial is equal to $\frac{1}{4}$ wave-length, so that there is a current node at the top of the antenna, and an anti-node at the base end thereof. The characteristic impedance of a vertical antenna of $\lambda/4$ height amounts to, let us say, 35 ohms. Hence, the surge impedance of the up-lead to feed the said antenna in the current loop (anti-node) should also be 35 ohms. An energy-feed line of this sort is easily obtained by two concentric tubes, the inner one of which may be a wire of thickness as shown and which is connected with the aerial, while the outer one is grounded. The outer tube could also be dispensed with provided the inner tube or wire is

correspondingly spaced apart from earth. At any rate in the case of such a $\lambda/4$ antenna recourse is had to a dissymmetric energy-feed line (Fig. 1). Since the radiation resistance of the antenna is determined by the length of the antenna and the operating wave length and must be kept constant, means are provided consisting of a drum C and a crank handle H to vary the length of the antenna as the wave length is changed. A weight W is attached to the inner 10 conductor of the transmission line.

Now referring to Figure 2, suppose the aerial has a length equal to $\frac{1}{2}\lambda$; then current nodes will be present at both ends, and an anti-node in the middle. The characteristic impedance of an aerial of $\frac{1}{2}$ wave-length amounts to, let us say, 70 ohms. The surge impedance of the energy-feed line for feeding in the current loop therefore should likewise be 70 ohms. In addition it should be symmetric (Fig. 2). Such an up-lead may be built up of two conductors spaced somewhat apart from each other, or else of two concentric cables whose outer envelopes are inter-connected, and which likewise may be grounded, such as shown in Fig. 3.

I claim:

1. In combination, an unloaded, quarter wave length, single wire, variable length, vertical antenna, high frequency apparatus, a horizontal transmission line of fixed length extending between said high frequency apparatus and said antenna and directly connected to said antenna, and means for varying the length of said vertical antenna for different wave lengths whereby the characteristic impedance of said transmission line always matches the radiation resistance of said antenna.

2. In combination, a linear, quarter wave length antenna, high frequency apparatus, a transmission line of fixed length extending from said high frequency apparatus to said antenna, said transmission line having a characteristic impedance substantially equal to the radiation resistance of said antenna, the antenna being adjustable to always equal a quarter wave length with change in frequency of said high frequency apparatus so that the radiation resistance is kept constant and matches the characteristic impedance of said transmission line.

3. A combination as defined in claim 2 characterized in this, that said transmission line comprises a concentric conductor cable having inner and outer tubes insulatingly separated throughout their lengths, said outer tube being connect-

ed to ground and said inner tube being connected to said antenna.

4. In an antenna system having high frequency apparatus, an antenna and a transmission line extending from said high frequency apparatus and directly connected to said antenna, the method of operation which comprises matching the characteristic impedance of said transmission line to equal the radiation resistance of said antenna and maintaining constant the value of the radiation resistance of said antenna for various lengths thereof.

5. In combination, an unloaded one quarter wave length antenna, high frequency apparatus, a concentric conductor transmission line comprising inner and outer tubes insulatingly separated throughout their lengths extending between said high frequency apparatus and said antenna and directly connected to said antenna, said outer

tube being connected to ground and said inner tube being connected to said antenna, the characteristic impedance of said transmission line matching the radiation resistance of said antenna, and means for adjusting the length of said antenna for different wave lengths.

6. In an antenna system having high frequency apparatus, an unloaded quarter wave length antenna of variable length, and a transmission line extending from said high frequency apparatus and directly connected to said antenna, the method of operation which comprises matching the characteristic impedance of said transmission line to equal the radiation resistance of said quarter wave length antenna and maintaining constant the radiation resistance of said antenna for different quarter wave length values thereof.
